UNITED STATES PATENT OFFICE.

FREDERICK S. HARMER, OF COLUMBUS, OHIO.

EXPLOSIVE-ENGINE.

1,012,635.

Specification of Letters Patent. Patented Dec. 26, 1911.

Application filed December 14, 1905. Serial No. 291,685.

To all whom it may concern:

Be it known that I, FREDERICK S. HARMER, a citizen of the United States, residing at Columbus, in the county of Franklin and 5 State of Ohio, have invented certain new and useful Improvements in Explosive-Engines, of which the following is a specification, reference being had to the drawings accompanying and forming part of the same.

10 My invention relates chiefly to systems for cooling the heated parts of an explosive engine, more particularly engines of the type in which the explosion chamber or cylinder is provided on its exterior with heat-radiating flanges, webs or ribs. It is common to absorb heat from such parts by causing a circulation of air or other gaseous cooling medium around and between the flanges, so as to cause a rapid absorption of 15 heat by the constant supplying of relatively cool air. The usual plan is to provide a blower, as for example, a disk-fan, in position to throw its blast directly on the flanged cylinder. It has also been proposed to provide a series of pipes or tubes, extending 20 transversely through the flanges. These pipes or tubes are connected with a suitable pump or blower, so that air may be circulated through them, with the intention of 25 absorbing the heat of the flanges more rapidly than is possible by simply blowing upon them, as in the method first mentioned above. I may state that, broadly considered, the plan of providing air tubes through the 30 flanges is an old and well understood expedient in the art.

My invention departs radically from all 35 the various constructions with which I am familiar. In the first place, I do not locate my air tubes transversely to the flanges—that is to say, extending through the flanges, from one flange to the other;—on the contrary, I locate the tubes or conduits entirely 40 within the flanges. Hence, where the flanges are arranged parallel to the axis of the cylinder, the conduits may be formed simply by 45 boring from end to end each or as many of the flanges as desired. These bores are then connected preferably with an air main which 50 is in turn connected with suitable means for blowing or drawing air through the conduits. I also prefer to combine with the conduit system, means for discharging air upon the exterior of the flanged cylinder, by 55 means of air jets located between the flanges so as to direct the currents of air along or

parallel and in contact with the flanges. With this arrangement the flanges are exposed both inside and out to cooling streams of air, with the result that the consequent 60 absorption of heat from the flanges is more rapid and more nearly uniform under all conditions of use than in any other system with which I am familiar.

The fundamental principle of my invention resides therefore in subjecting the flanges to a gaseous cooling medium by circulating such medium through the interior of the flanges, by means of pipes or conduits lying within the same, as opposed to 65 extending across them. With this system I may, if desired, combine the feature of subjecting the exterior of the flanges also to air currents.

The nature of the invention can be more 70 readily understood from a description of the preferred embodiment, and the same is therefore illustrated in the annexed drawings.

Figure 1 is a side elevation, partly in section, of an internal combustion engine embodying my improvements. Fig. 2 is a vertical sectional view, taken on line I—I, Fig. 1, showing one of the cylinders and various other parts. Fig. 3 is a horizontal section 80 through a cylinder, showing the arrangement of heat-radiating ribs or flanges, with the air conduits. Fig. 4 is top plan view of a cylinder with the valves and igniting devices removed. (Fig. 5 is a vertical section 85 on a plane at right angles to that of Fig. 2. Fig. 6 is a vertical longitudinal sectional view showing a convenient fan or blower, and the driving mechanism therefor. Fig. 7 is an end view of the centrifugal clutch device for connecting the fan or blower with its driving mechanism. Fig. 8 is a detail view in side elevation of the rotating fan.

Referring now more particularly to Fig. 1, A indicates the cylinders, one or more in 90 number, of any approved type of internal combustion engine, the said cylinders being preferably arranged with their axes vertical, as shown, in accordance with the prevailing practice in the case of engines designed for driving automobiles. B is the crank case, and C the usual fly-wheel. Each cylinder is provided with numerous heat-radiating ribs as a Figs. 2, 3, 4, and 5, and each rib is preferably divided, as clearly shown 95 in Fig. 3, to provide two fins, a' a'. By preference the ribs are parallel with the axis 100 105 110

of the cylinder, that is, they extend longitudinally thereof. In each rib is a conduit, as a^2 , formed by a suitable core when the cylinder is cast, or drilled out afterward. If desired the conduit may be provided with an inner tube or lining, as a^3 . These tubes may be placed in position after the bores are formed, or they may be placed in the mold in which the cylinder is cast, in which case they constitute the cores which produce the bores or conduits. The ribs a and fins a' extend some distance down the cylinder, preferably at least to the lower limit of the travel of the piston D. At the lower ends of the ribs is a casing A' through which the cylinder or cylinders extend. This casing constitutes a main for carrying air to the conduits a^2 , which open into it at their lower ends. At the end of the engine opposite the flywheel is a blower, connected to a branched pipe A², the lower branch of which delivers the air to the main A'. The upper ends of the conduits a^2 are open, and discharge freely into the atmosphere.

The cylinder head is preferably spherical or dome-shaped, as shown in Figs. 1 and 2, and on opposite sides of the same are valved passages, indicated by a^4 , a^5 , one for supplying the combustible gas to the cylinder and the other for discharging the products of combustion. Between these passages the head or dome is provided with ribs, a^6 , Figs. 4 and 5, each having an air conduit, like the ribs on the side of the cylinder. These conduits converge and open into a central chamber A³ on top of the cylinder head, and each chamber is connected with an upper main A⁴, which is in turn connected with the upper branch of the pipe A² leading from the fan or blower. The lower ends of the head conduits are open, and are located so as to discharge downwardly between, and parallel with, ribs on the sides of the cylinder.

The operation of the cooling system will now be readily understood. Air from the blower flows along the lower main, A', and is delivered to the various conduits in the vertical ribs, absorbing heat therefrom and finally issuing against the latter ribs on the head, as will be seen by the arrows in Fig. 2, thereby having some cooling effect on these ribs as well as on the others. At the same time air flows along the upper main A⁴ to the chambers at the tops of the cylinders, from whence it passes into the head conduits, absorbing heat from the head and finally issuing between vertical ribs on the sides of the cylinder. The result is a very rapid cooling of the heated parts of the engine.

It will be observed that the spark plug, E, is located in the head chamber, so that it is continually bathed by the current of cool air coming from the upper main. This

arrangement is an important feature of my invention.

It is desirable that the valved passages a^4 , a^5 , and parts connected therewith be kept cool, and for this purpose I provide each of these valve casings with an external circumferential passage a^7 . When the casings are in place, as in Fig. 2, the passages register with openings a^8 leading to the air chamber A³ and into discharge apertures a^9 near the vertical ribs a . The air from the chamber entering the first mentioned openings divides in each case, and flows around the valve casing, finally issuing through the various apertures around the passage. By this means the cooling of the valve and passage is materially improved, and the means whereby this improved effect is attained is also an important feature of my invention.

The fan or blower is inclosed in a suitable casing F, provided with central openings for the admission of air and located at the end of the crank shaft F'. The fan itself consists of a hub f, provided with spokes f', in the ends of which are secured rings or rims f². Extending axially between and secured to the rings are the buckets or blades f³. The latter are preferably of the scoop form shown in Fig. 8, and may be made by stamping from sheet metal a blank and bending the same into the proper form. Extending axially from the hub f is a gear rim g, meshing with a gear g' on counter-shaft g². The countershaft also has a gear g³, meshing with a gear g⁴ on the hub g⁵ rotatable about the sleeve h on the crank shaft F'. The gear g⁴ is hollow, and within the same are the centrifugally actuated friction clutch devices shown in Fig. 7. On the sleeve h, which is keyed to the shaft F', are oppositely extending radial arms h', to which are pivoted the weight levers h², which are in turn connected by links h³ to friction shoes h⁴ adapted and arranged to engage the inner surface of the hollow gear g⁴ when the levers or arms h² are thrown out by centrifugal force, as will happen when the engine is started. In this way the sudden torque of the engine is communicated slowly and gently to the fan, so that the same is relieved of any injurious strains when the engine starts. The blower and driving mechanism just described are likewise important parts of my invention.

It will be observed that the lower air main, A', is in communication with the interior of the cylinder through one or more ports p, p, located below the position of the piston when at the upper end of its travel, so that air from the air main A' is admitted to cool the interior of the cylinder below the piston whenever the ports p, p, are uncovered. The openings p', p', are oil drain ports, serving also as auxiliary air ports from the main. These features are novel

and form part of my invention, but may or may not be used, as desired. Another feature of value is the dome-shaped cylinder head and concave piston, producing a spherical explosion chamber, as shown in Fig. 2.

The specific elements and the particular arrangement thereof herein described constitute merely the preferred embodiment of my invention, which of course may be embodied in a variety of forms without departure from its proper scope, which I believe to be defined by the following claims.

What I claim is:

1. In an internal combustion engine, the combination of two or more cylinders, each provided with heat-radiating ribs or flanges extending longitudinally of the said cylinders, each rib or flange being provided with an internal longitudinal air conduit, an air main common to the air conduits of the several cylinders, a blower, driving mechanism between the engine and the blower to actuate the latter, and means for delivering air from the blower to the said air main, as set forth.

2. In an internal combustion engine, the combination of a cylinder provided on its sides with longitudinal heat-radiating ribs or flanges having internal air conduits and provided with radially extending heat-radiating ribs or flanges on its head, also having internal air conduits, a blower, means for connecting the blower with the inner ends of the conduits in the said radial ribs or flanges, and means for connecting the blower with the ends of the longitudinal conduits, farthest removed from the cylinder head, as set forth.

3. In an internal combustion engine, the combination of a plurality of vertical cylinders each provided with vertical air conduits, heads for the cylinders, each provided with air conduits extending radially from the center of the head, a blower, an air main connecting the blower and inner ends of conduits in the cylinder heads, and an air main connecting the blower and the lower orifices of the vertical conduits, as set forth.

4. In an internal combustion engine, the combination of a cylinder provided with longitudinal air conduits open at the head of the cylinder, a blower connected with the other ends of the conduits, a head for the cylinder provided with air conduits extending radially and having their outer ends open and adjacent to the open ends of the longitudinal conduits, and means for connecting the blower with the inner ends of the radial conduits, as set forth.

5. In an internal combustion engine, the combination of a cylinder provided with longitudinal heat-radiating ribs having air conduits therein open at the head of the cylinder, a blower connected with the ends of the conduits farthest from the head, radial-

radiating ribs or flanges on the cylinder head, terminating adjacent to the open ends of longitudinal conduits, in staggered relation thereto and provided with air conduits open at their outer ends, and means for connecting the inner ends of the radial conduits with the blower; whereby air will flow through the radial conduits and be discharged between and parallel with the adjacent longitudinal ribs or flanges; and through the longitudinal conduits and be discharged between the adjacent ribs or flanges on the cylinder head; as set forth.

6. The combination of an internal combustion engine having a crank shaft, a blower rotatably mounted on the crank shaft, for supplying air to cool the engine, and means for operatively connecting the blower with the crank shaft to drive the former, the said means including a centrifugally actuated clutch, as set forth.

7. The combination of an internal combustion engine having a crank shaft, a rotary blower for supplying air to cool the engine, said blower being rotatably mounted on the crank shaft, a counter shaft operatively connected with the crank shaft, and mechanism connecting the counter shaft with the blower to drive the latter, the said mechanism including a centrifugally actuated clutch, as set forth.

8. In an internal combustion engine, the combination of a plurality of cylinders arranged side by side, longitudinally extending heat-radiating ribs on the cylinders, provided with internal air conduits, an air main extending across the cylinders and communicating with the several air conduits in the ribs, and a blower arranged to deliver air to said main, as set forth.

9. In an internal combustion engine, in combination, a plurality of cylinders having side walls provided with ports adapted to be uncovered by the engine pistons in their inward travel and to be closed by the pistons in their outer positions, and an air main conveying air to the cylinders to cool the exterior thereof and communicating with the interior of the cylinders through said ports whereby to deliver cool air into the cylinders to cool the same and their pistons.

10. In an internal combustion engine, in combination, a cylinder having in its side wall one or more ports adapted to be uncovered by the engine piston in its inward travel and to be closed by the piston when the same is in its outer position, and an air main conveying cool air to cool the exterior of the cylinder and communicating with the interior of the cylinder through said port or ports, whereby cool air will be delivered to the interior of the cylinder from the air main, as set forth.

11. In a driving device for engine fans, the combination with an explosive engine

adapted to variable loads and speeds, and a fan adapted to cool the engine; of a driving connection between the engine and the fan comprising a frictional driving mechanism and centrifugally actuated means for varying the frictional engagement of the mechanism as the speed of the engine varies.

12. In a driving device for engine fans, the combination with an explosive engine 10 adapted to variable loads and speeds, and a

fan adapted to cool the engine; of a driving connection between the engine and the fan comprising a clutch and a centrifugally actuated automatic means for throwing the clutch into and out of engagement as the speed of the engine varies. 15

FREDERICK S. HARMER.
